UNITED STATES PATENT OFFICE.

OSCAR H. PIEPER AND ALPHONSE F. PIEPER, OF ROCHESTER, NEW YORK.

DESIGN FOR A DENTAL-APPLIANCE PANEL.

58,819.

Specification for Design.

Patented Aug. 30, 1921.

Application filed October 22, 1920. Serial No. 418,833. Term of patent 14 years.

To all whom it may concern:

Be it known that we, OSCAR H. PIEPER and ALPHONSE F. PIEPER, both citizens of the United States, residing at Rochester, in the county of Monroe and State of New York, have invented a new, original, and ornamental Design for a Dental-Appliance Panel, of which the following is a specification, and of which the accompanying drawing is a representation.

Figure 1 is a front view of a panel for dental appliances showing our new design, and

Fig. 2 is a side view of the same.

We claim:

The ornamental design for a dental appliance panel, as shown.

OSCAR H. PIEPER.
ALPHONSE F. PIEPER.
